ANTISKID DEVICE

Paul E. Wimmenauer, Washington, Ind.

Application December 16, 1937, Serial No. 180,253

1 Claim. (Cl. 36—7.7)

My invention relates to improvements in anti-skid devices for attachment to the soles of shoes to obviate slipping on icy pavements or other slippery surfaces.

5 The invention is designed with the particular purpose in view of providing an efficient, durable and inexpensive attachment of the character above indicated which may be quickly and securely attached to shoe soles and detached therefrom, made in different sizes to fit different sizes of shoe soles and will not mar or otherwise injure the shoe sole to which it is attached.

To the accomplishment of the above and subordinate objects presently appearing a preferred embodiment of my invention has been illustrated in the accompanying drawings, set forth in detail in the succeeding description, and defined in the claim appended hereto.

In said drawings:—

20 Figure 1 is a view in side elevation of a shoe equipped with my improved anti-skid device,

Figure 2 is a view in bottom plan,

Figure 3 is a view in perspective of one of the calks,

25 Figure 4 is a view in top plan of the device detached,

Figure 5 is a view of the stud for the coupling shown in perspective,

Figure 6 is a similar view of the bracket for 30 connecting the coupling to the auxiliary sole, and

Figure 7 is a view in perspective of one of the toe clips.

Referring to the drawings by numerals, the anti-skid device of my invention comprises an auxiliary half-sole 1 for attachment to the bottom of a shoe sole and which may be made of any suitable material such as composition rubber, leather, or the like, in the different contours and sizes of the soles of different sizes of shoes to fit 35 flush thereagainst. The auxiliary sole is provided with a plurality of stud-like calks 2 extending from the bottom thereof and arranged preferably in transversely extending rows in any desired spacing in each row suitable to prevent slipping. The calks 2 are a particular feature of my invention. Each calk 2 comprises a tubular longitudinally split shank 3 extending through the auxiliary sole 1, a circular flange 4 abutting the bottom of the sole 1 and a ground engaging solid cylindrical spur 5. The shank 3 is riveted in the usual manner on the upper side of the sole 1 over a burr 6 indicated in dotted line in Figure 4. Preferably the described calk 2 is formed by 50 a split copper rivet comprising the shank 3

brazed to the head of a cut-off nail forming the flange 4 and spur 5.

The auxiliary sole 1 is detachably secured to the sole 7 of a shoe as follows. A pair of toe clips 8 of resilient flat metal are secured to the top of the auxiliary sole 1, as by copper rivets 9, to extend forwardly from the toe 10 thereof upon opposite sides of the longitudinal center of said sole 1, said clips 8 having hooked front ends 8' adapted to take rearwardly over and grip the toe 10 part of the shoe sole 7 upon opposite sides of said toe part. At the rear edge 10' of the auxiliary sole 1, which is made straight, is a tubular bracket 11 secured along said edge 10' by means of ears 12 extending from the same adjacent opposite ends thereof, respectively, and riveted, as at 13, to the top of said sole 1. Extending from the bracket 11 is a bail-like coupling 14 of resilient wire and bellows-like form having at one end thereof opposed terminal legs 15 journaled in 20 opposite ends of the bracket 11, zigzag sides 16, and a loop 17 at its opposite end. The coupling 14, as will be understood, is adapted to lie flat in the instep part of the shoe and to be connected thereto in a tensioned condition to pull the clips 25 8 tight and anchor the device in fixed position. For connecting the coupling 14, a headed stud 18 is secured to the instep part of the shoe sole 7, said stud 18 having a base plate 19 nailed, as at 30 20, to said shoe sole 7.

As will now be seen the described coupling 14 exerts a tension against the auxiliary sole 1 rearwardly and sufficient to retain the clips 8 in position and together with said clips secure the auxiliary sole in position while at the same time by 35 pulling rearwardly on the coupling 14 the latter may be detached from the studs 18 and the device quickly removed by pushing forward to detach the clips 8.

The foregoing will, it is believed, suffice to 40 impart a clear understanding of the invention without further explanation.

Manifestly the invention as described is susceptible of modification without departing from the inventive concept and right is herein reserved to 45 all such modifications falling within the scope of the subjoined claim.

What I claim is:

An anti-skid device for attachment to the sole of a shoe comprising an auxiliary half-sole having 50 calks extending from the bottom thereof, a pair of toe clips secured to the toe part of said auxiliary sole to extend therefrom upon opposite sides of said toe part, respectively, and having hooked front ends adapted to take over the 55

toe part of the shoe sole, and means to couple the rear edge of said auxiliary sole to the instep part of the shoe sole, said means exerting a tension rearwardly on said auxiliary sole and comprising a stud secured to said instep part, and a ball-like coupling of resilient wire and bellows

form pivoted to the rear edge of said auxiliary sole and hooking over said stud, said coupling lying flat in said instep part to function as an anti-skid device therein.

PAUL E. WIMMENAUER.
